(57) **CLAIM**

The ornamental design for an escutcheon, as shown and described.

DESCRIPTION

FIG. 1 is a perspective view of an escutcheon showing my new design;

FIG. 2 is a front elevational view thereof;

FIG. 3 is a rear elevational view thereof;

FIG. 4 is a left side elevational view thereof, the right side elevational view being symmetric to the left side elevational view; and,

FIG. 5 is a top plan view thereof, the bottom plan view being symmetric to the top plan view.

The broken line showing of the cover of the escutcheon in FIGS. 1, 2 and 3 is for illustrative purpose only and forms no part of the claimed design.

1 Claim, 2 Drawing Sheets

FIG. 1

FIG. 2

FIG. 3

FIG. 4

FIG. 5

UNITED STATES PATENT AND TRADEMARK OFFICE
CERTIFICATE OF CORRECTION

PATENT NO. : Des. 513,166 S
DATED : December 27, 2005
INVENTOR(S) : Tsung-Chung Huang

Page 1 of 1

It is certified that error appears in the above-identified patent and that said Letters Patent is hereby corrected as shown below:

Title page.

Item [73], Assignee, replace with -- **Tong Lung Metal Industry Co., Ltd.** --

Signed and Sealed this

Twenty-eighth Day of March, 2006

A handwritten signature in black ink, appearing to read "Jon W. Dudas", is centered within a rectangular dotted box.
